UNITED STATES PATENT OFFICE.

WILLIAM E. ELAM, OF WASHINGTON, DISTRICT OF COLUMBIA.

SHOE-BLACKING DEVICE.

1,147,490.

Specification of Letters Patent. Patented July 20, 1915.

Application filed January 28, 1915. Serial No. 4,915.

To all whom it may concern:

Be it known that I, WILLIAM E. ELAM, a citizen of the United States, residing at Washington, in the District of Columbia, have invented certain new and useful Improvements in Shoe-Blacking Devices, of which the following is a specification, reference being had therein to the accompanying drawing.

10 The general object of this invention is to provide devices for storing and applying to shoes ordinary paste blacking.

In the accompanying drawings, Figure 1 is a side elevation of the device, parts being broken away. Fig. 2 is a view looking from the right in Fig. 1, the cover being omitted and a portion of the handle being broken away. Fig. 3 is a view looking in the direction of the arrow of Fig. 1 but showing only 20 a cap seen in that figure. Figs. 4, 5 are partial views showing different modifications.

In Figs. 1, 2 and 3, A represents a preferably rectangular casing which may be of metal, primarily open at each end and having the plane of one end oblique to the axis.

B represents a block fixed and fitting in one side of the interior space and provided with a lip B' between which and the edge of the narrow side of the casing there is formed 30 a compartment in which a small brush C is removably secured by screws or otherwise to project slightly beyond the oblique end plane of the casing, at the most advanced portion thereof. Over the side walls of this portion 35 of the casing fits a cup-like pliable member D, which may be of leather, the body or bottom of which is parallel to and at a little distance from the oblique end plane of the casing and is provided with numerous openings. The flange D' of the cup is secured to the casing walls in any suitable way, for example, by cement and by spurs A' stamped out from the casing walls, passing through 40 the flange and bent down thereupon. To 45 allow the flange to pass over the spurs, it may be cut as shown at D² to form flaps which are preferably held down by additional spurs.

Within the casing works a plunger E having a suitable handle F, and the space between the plunger and the member D is filled with ordinary blacking G, which is pressed against the member D when the plunger is advanced. At a suitable point in 55 its length the casing is perforated, as at H,

to allow the escape of any air that may be trapped in front of the plunger.

The blacking space is preferably of substantially the same capacity as the ordinary blacking box. Obviously, pushing the blacking forward forces it into the perforations in the member D, and if this pliable end be moved over a shoe while gently pressed thereon blacking will be applied, and if the movement be in the proper direction so that the brush follows the body or main part of the end, the brush completes and perfects the distribution. The amount of blacking applied is readily varied by varying the inclination of the implement. The member D is cut along the outer side of the brush space and the flap D² thus formed is turned inward over the lip B' so that no blacking can reach the brush except such as is first distributed upon the shoe,—which is a matter of importance. The brush which owing to the form of the casing is at the tip of a wedge serves very satisfactorily for applying the blacking in the angle next the shoe sole.

When the supply of blacking is nearly exhausted, the plunger may be removed and the blacking space be refilled, the well known collapsible tube forming a convenient device to be used in recharging. When the device is not in use its working end may be covered by a closely fitting cap K, preferably having its end face non-inclined.

Fig. 4 shows a plunger L arranged to be advanced by a screw M working in a nut N rigidly connected with the casing.

Fig. 5 shows in elevation a form in which the plunger is omitted and the body of the casing and block B are replaced by a collapsible tube O, the device however, having the inclined working end face and the brush at the tip of the wedge, and an oblique cover K'.

The form shown in Fig. 5 is so inexpensive that it may be discarded when the original charge is exhausted.

The inclination of the applying face may vary from zero to any desired maximum, but is usually about as shown.

What I claim is:

1. In devices of the class described, a blacking receptacle having an inclined and perforated end face and a pliable brush fixed alongside the more advanced margin of said face, and means for forcing the

blacking outward through said perforations, as desired.

2. In a shoe blacking device, the combination with a blacking receptacle having a working face of pliable material provided with perforations adapted to allow paste blacking under pressure to pass freely, of means for at will applying pressure to blacking within the receptacle, and a face-following brush fixed adjacent to said working

Copies of this patent may be obtained for five cents each, by addressing the "Commissioner of Patents, Washington, D. C."

face and having its own working face approximately in the plane of the working face first mentioned.

In testimony whereof I affix my signature in presence of two witnesses.

W. E. ELAM.
